Patented Nov. 5, 1918.

UNITED STATES PATENT OFFICE.

SUTTON R. BUCHANAN, OF NEW BREMEN, OHIO.

LIGHTNING-ARRESTER.

1,283,651.

Specification of Letters Patent.

Patented Nov. 5, 1918.

Application filed April 22, 1918. Serial No. 230,091.

To all whom it may concern:

Be it known that I, SUTTON R. BUCHANAN, a citizen of the United States, residing at New Bremen, in the county of Auglaize and State of Ohio, have invented certain new and useful Improvements in Lightning-Arresters, of which the following is a specification, reference being had to the accompanying drawings.

10 This invention relates to an improved lightning arrester, and has for its primary object to provide a lightning arrester which is particularly designed for use as a protection for low potential telephone lines 5 against the destructive effects of lightning or other high potential currents.

It is a more particular object of the invention to provide a lightning arrester of the character stated designed for use in connection with the individual current conducting wires.

It is also an important object of the invention to provide a device for the above purpose which will afford a satisfactory insulator for the line wire as well as a rigid and durable support.

It is an additional object to provide a lightning arrester of such construction that the lightning or other dangerous high potential current is diverted from the line wire to the ground, while at the same time the line wire is completely insulated from the ground.

The invention also has for a further object to provide a construction wherein the gap between the high and low potential current conducting elements is always uniform, and wherein these elements are also completely housed and protected against the deteriorating effects of the elements and from the collection of foreign matter thereon which would seriously interfere with the proper operation of the device.

And it is a further general object of my invention to provide a lightning arrester for telephone lines, which is relatively simple in its construction, can be manufactured at very small cost, and is readily adaptable to the standard type of insulating post now in general use.

With the above and other objects in view, the invention consists in the improved construction, combination and relative arrange-

ment of the several parts as will be herein-after more fully described, subsequently claimed and illustrated in the accompanying drawing in which similar reference characters designate corresponding parts throughout the several views, and wherein:

Figure 1 is a side elevation illustrating one embodiment of my improved lightning arrester;

Fig. 2 is a longitudinal section taken on the line 2—2 of Fig. 1;

Fig. 3 is a section taken on the line 3—3 of Fig. 2;

Fig. 4 is a fragmentary perspective view of the fastening bolt for the insulator post; and

Fig. 5 is a vertical sectional view illustrating a slightly modified construction, the insulator being removed.

Referring in detail to the drawing, 5 designates an insulator which may be formed of porcelain or other suitable material and is preferably of cylindrical shape, said insulator gradually tapering or decreasing in diameter from one end to the other thereof. This insulator is formed exteriorly with spaced annular grooves 6 to receive the wires carrying a low potential current. The insulator body is also longitudinally bored and threaded as at 7, said bore having an unthreaded outwardly flaring portion 8 at the larger end of the insulator. At the inner end of the bore 7 the insulator is formed with a chamber 9, and diametrically opposed radially extending openings 10 connect this chamber with one of the annular grooves 6 in the periphery of the insulator.

The supporting post or pin 11 for the insulator body 5 is of the usual form, said post tapering longitudinally and having a coarse peripheral thread 12 on one end thereof, for engagement with the threaded bore 7 of the insulator body. The wall of the insulator body, at the outwardly flaring end of the bore 7, constitutes an annular skirt 13 surrounding the supporting post or pin 11 in spaced relation thereto. The skirt 13 insures a dry insulating surface in wet or stormy weather.

The post or pin 11 is also longitudinally bored as at 14 to receive the attaching bolt or rod 15, which is of such length that said rod may be readily mounted upon the usual

supporting arm and the post 11 securely clamped in place by means of the nut 16 threaded on the end of said bolt.

The post 11 is provided at its smaller end 5 and in the end face thereof with a rectangular seat having the beveled or inclined faces 17. The attaching bolt 15 at its upper end is also provided with a rectangular portion having outwardly inclined lateral faces 18 for engagement on the seating faces 17. To this rectangular end of the bolt, a circular disk or plate 19, preferably of brass, is suitably secured.

In the channel or groove 6 with which 15 the transverse openings communicate, the metal strips 20 are arranged, said strips being both transversely and longitudinally curved to fit snugly against the wall of said groove. Each of these strips is centrally 20 provided with an opening to receive a screw 21. These screws at their inner ends have threaded engagement in the opposite sides of a circular brass plate or disk 22 which is disposed within the chamber 9 of the insulator body. Between the lower face of 25 this disk and the opposed face of the plate or disk 19 on the end of the bolt 15, a circular sheet of mica or other suitable dielectric material 23 is interposed, said mica disk 30 having a plurality of openings 24 therein to facilitate the passage of a high potential current.

The several parts of the device being assembled as shown in Fig. 2 of the drawing, 35 the operation is as follows. The bare telephone line wire is tied or otherwise suitably fastened in the top groove 6 of the insulator body and in contact with the metal strips 20 so that an electrical connection is made 40 from the line wire through the strips 20, the screws 21 and the metal disk 22. A wire connected to the attaching bolt 15 leads to the ground. There is thus established a complete circuit for a high potential current 45 which may be impressed upon the telephone line wire, the said current easily bridging the gap between the metal disks 22 and 19 formed by the mica disk 23 so that this current will be diverted from the line wire and conducted to the ground. Normally, it will be understood that the 50 telephone line wire is completely insulated from the ground connection by the mica spacing disk 23.

In Fig. 5 of the drawing, I have shown a slight modification of the device which renders my invention adaptable to the standard form of insulator supporting post or pin without necessitating alterations of any 60 character whatever therein. In this modification, I provide a sleeve or jacket generally designated by the numeral 25, which is of a suitable current conducting metal. This jacket is formed with a threaded section 26 65 for engagement with the threads of the sup-

porting post or pin. The jacket is diametrically enlarged or outwardly flared at one end as at 27 and provided with an apertured ear 28 or other suitable means for the connection of the ground wire thereto. The 70 other end of the jacket 25 is closed and to the outer face thereof the plate or disk 29, corresponding to the metal disk 19 above referred to, is suitably secured. In connection with this metal jacket, an insulator 75 having the current conducting means above described is used. It will be apparent, of course, that in the modified construction, the device will operate in practice precisely in the same manner as in the first described 80 embodiment of my invention.

From the foregoing description taken in connection with the accompanying drawing, the construction, manner of operation and several advantages of my improved lightning arrester will be fully understood. By the provision of an arresting device for lightning or other high potential currents for the individual wires, telephone systems may be adequately protected. As the several 85 parts of the invention are of exceedingly simple form, the device may be installed in telephone line systems at only slightly greater expense than is incident to the equipment of the lines with the ordinary 90 standard type of insulators. My invention provides means which affords a very rigid and substantial support for the line wire as well as means whereby the wire is completely insulated from the ground, while 1 at the same time the high potential currents are diverted from the line wire. It is likewise to be noted that by mounting the conducting plate 22 within the insulator in the manner described, the gap between this plate 1 and the head plate 19 on the attaching bolt will likewise be uniform throughout the surface area of said plates. The gap or space separating the element 22 from the head plate 19 is as small as possible without being 1 in actual contact so that the high potential currents will readily bridge or jump this gap. These plates being arranged within the chamber 9 of the insulator body and the openings 10 being securely closed by the metal strips 20, said plates are completely housed and protected from the elements or the entrance of insects or other foreign matter between said plates, which would be likely to interfere with the proper working of the telephone lines and the discharge of the high potential currents.

I have herein shown and described what I have found to be a very satisfactory construction and arrangement of the several elements, but it is to be understood that in practice the exigencies of the particular case may require certain structural changes in the various parts. As these parts are obviously susceptible of many minor modifi-

cations, it is therefore to be understood that I reserve the privilege of adopting all such legitimate changes as may be fairly embodied within the spirit and scope of the 5 invention as claimed.

I claim:—

1. In combination, a relatively fixed current conducting member adapted to be connected to the ground, an insulator body 10 mounted upon said current conducting member and having a chamber therein, a current conducting element disposed within said chamber in opposed relation to the fixed conductor, said insulator body having exterior 15 means for the connection of a line wire thereto, and means mounted in the insulator body for establishing an electrical connection between the line wire and said current conducting element, said means also suspending the element in spaced relation to the fixed conductor.

2. In combination, a relatively fixed current conducting member adapted to be connected to the ground, an insulator body having a bore to receive said member and provided with a chamber at the inner end of 25 said bore, a current conducting element in said chamber in opposed relation to said fixed member, a sheet of dielectric material 30 interposed between said current conducting element and the fixed member, said insulator body having exterior means for the connection of a line wire thereto, and means for closing the circuit between said line 35 wire and said current conducting element.

3. In combination, a relatively fixed current conducting member adapted to be connected to the ground, an insulator body having a bore to receive said member and provided with a chamber at the inner end of 40 said bore, a current conducting element in said chamber in opposed relation to said fixed member, said insulator body having exterior means for the connection of a line 45 wire thereto, and radially disposed circuit closing members mounted in the insulator body for engagement by the line wire, said members being connected to the current conducting element to position said element in uniform spaced relation to the fixed member.

4. In combination, a relatively fixed current conducting member adapted to be connected to the ground, an insulator body having a bore to receive said member and provided with a chamber at the inner end of 55 said bore, a current conducting element in said chamber in opposed relation to said fixed member, said insulator body having

exterior means for the connection of a line wire thereto, radially disposed circuit closing members mounted in the insulator body for engagement by the line wire, said members being connected to the current conducting element to position said element in uniform spaced relation to the fixed member, 60 and a perforated sheet of dielectric material interposed between said circuit closing element and the fixed member.

5. In combination, a relatively fixed current conducting member adapted to be connected to the ground, an insulator body bored to receive said member, said body having an exterior line wire receiving groove, metal strips snugly fitting the wall of said groove for engagement by the line wire, a 70 current conducting element arranged in the bore of the insulator body, circuit closing means connecting said element to said metal strips, and supporting said element in opposed relation to the fixed current conducting member, and a sheet of dielectric material interposed between the fixed member and said element.

6. In combination, a relatively fixed current conducting member adapted to be connected to the ground, an insulator body bored to receive said member, said body having an exterior line wire receiving groove and transverse openings connecting said groove with the bore, metal strips arranged 85 in said groove and engaged by the line wire, a circuit closing element, screws connecting said metal strips to said element and supporting the element in opposed relation to said fixed member, and a perforated sheet of 90 dielectric material interposed between the fixed member and said element.

7. In combination, an insulator post and an attaching bolt extending therethrough having a head on one end, an insulator body 100 adapted to be detachably threaded upon the post and having an annular skirt disposed in spaced relation to the threads on the post, the insulator body having exterior means for fastening the line wire thereto, and 105 means carried by the insulator for grounding a circuit from the line wire including a current conducting element, and a sheet of dielectric material spacing said element from the head on the attaching bolt.

In testimony whereof I hereunto affix my signature in the presence of two witnesses.

SUTTON R. BUCHANAN.
